STOVE

**Bertrand B. Kahn, Cincinnati, Ohio, assignor to
The Estate Stove Company, Hamilton, Ohio, a
corporation of Ohio**

Application August 24, 1931, Serial No. 559,047

7 Claims. (Cl. 158—115)

This invention relates to stoves.

One of the principal objects of the invention is the provision of a stove having a member of simple construction which serves as a support for the cooking surface, and also extends beneath the cooking surface as an interceptor, having channels for directing fuel flow from the burners to a pilot light for ignition therefrom.

10 Another object of the invention is the provision of an interceptor plate which is integrally formed from sheet metal and is grooved for reception of a cover piece which cooperates with the grooves to provide fuel flow passages for flashback ignition of the stove burners from a pilot light.

15 light. Other objects and advantages of the invention will be apparent from the following description, the accompanying drawing, and the appended claims.

20 In the drawing, which discloses a preferred embodiment of the invention,

Fig. 1 is a plan view of a stove constructed in accordance with the present invention; certain of the parts being broken away for clearness in illustration;

28 Fig. 2 is a vertical sectional view taken on the line 2—2 of Fig. 1;

Fig. 3 is a vertical sectional view taken on the line 3—3 of Fig. 1, and

30 Fig. 4 is a fragmentary vertical sectional view taken on the line 4—4 of Fig. 1.

The drawing, in which like characters of reference designate like parts throughout the several views thereof, illustrates a stove of the kitchen range type having a top member 10 which as shown is integrally formed of sheet metal. The member 10 comprises a rim portion 11 which is in the shape of a rectangular frame having a flat top portion 12. At the inner edge of the rim 11 a

40 depression 13 is formed which serves as a seat for the support of a cooking surface 14 shown as a grille composed of spaced bars. A flange portion 15 continues downwardly and inwardly from the depression 13 and terminates at a plate portion 16 which forms a closure for the area defined by the rim 11. The plate portion 16 extends across the entire area within the flanges 13 of the rim sides and, except for openings 17 in which the stove burners 18 stand, the plate provides a closure which serves as an effective interceptor 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330

for the burner heat. The relative proportioning of the parts of the member 10 is such that sufficient vertical height is provided between the depression 13, upon which the grille 14 is carried, and the surface of the plate portion 16, so that

the burners 18 may be mounted at substantially the level of the plate 16 and will stand properly spaced from the grille-14 upon which the cooking vessels rest.

The plate portion 16 of the top member 10 is constructed to provide for flash-back ignition of the burners 18 from a pilot light 20 which, like the burners 18, is supported in some suitable manner from the stove structure. Ignition of the burners 18 from the pilot 20 is accomplished by provision of channels in the plate portion 16 which serve to direct a flow of fuel from each burner to the pilot light so that upon ignition of this fuel at the pilot the flash of the burning fuel then carries back through the channel for ignition of fuel issuing from the burner jets. As shown, a depressed central portion 22 is formed at substantially the mid-point of the plate portion, and from this portion 22 depressed grooves 23 extend which terminate adjacent the burners 18 at the burner openings 17 of the plate. The depressed portions of the plate are formed therein during the fabrication of the member 10 and thus serve as simple means of providing channels whereby fuel may be conducted from the burners to the pilot.

A cover member 24 is provided for the depressed portions of the plate and cooperates with the grooves to form fuel flow passages. As shown, the plate 24 is a simple spider shaped casting 30 having a central portion 25 which overlies the depressed portion 22, and outwardly extending arms 26 which overlie the grooves 23. The cover arms 26 have spaced downwardly extending ribs 27 which lie between the side walls of the grooves 23 and thus serve to form a substantially closed 35 passage as well as provide a locating means for properly positioning the cover member over the grooves.

As shown, the pilot light 20 stands beneath the plate portion 16 and is positioned concentrically with respect to an opening 30 in the depressed portion 22 and an opening 31 in the cover 24 which stands vertically related to the opening 30. 40

which stands vertically related to the spring 45
While the form of apparatus herein described constitutes a preferred embodiment of the invention, it is to be understood that the invention is not limited to this precise form of apparatus, and that changes may be made therein without departing from the scope of the invention which is defined in the appended claims. 50

What is claimed is:

What is claimed is:

1. In a stove, a plurality of burners, a pilot light, and an integrally formed sheet metal member comprising a rim portion, said rim portion having

- a depression therein at the inner edge for support of a cooking surface, a downwardly and inwardly extending flange projecting from the rim depression, and a plate portion extending from 5 the flange and forming a closure for the rim portion, said plate portion having burner openings therein and fuel conducting channels extending between the pilot and the burners, said channels being formed as depressions in the plate portion, 10 and a readily removable cover member overlying said channels and cooperating therewith to form fuel conducting passages for flash-back ignition of the burners.
2. In a stove, a plurality of burners, a pilot light, 15 a plate extending between said burners, said plate having a depressed fuel conducting groove formed therein between the pilot light and a burner for flash-back ignition of the said burner and a readily removable cover overlying the groove and 20 cooperating therewith to form a fuel conducting passage.
3. In a stove, a plurality of burners, a pilot light, an interceptor plate extending between said 25 burners, said plate having depressed grooves formed therein extending between the pilot and the burners, and a readily removable cover member overlying said grooves and cooperating therewith to form fuel conducting passages for flash-back ignition of the burners.
4. In a stove, a plurality of burners, a pilot light, an interceptor plate extending across the 30 burner space and having burner openings therein, said plate having depressed grooves formed therein extending between the pilot and the burners, and a cover member removably received in said grooves and cooperating therewith to form fuel conducting passages for flash-back ignition of the burners.
5. In a stove, a plurality of burners, a pilot light, an interceptor plate extending between said 35 burners, said plate having a depressed central portion and depressed outwardly extending grooves formed therein, said grooves terminating adjacent the burners, and a flat cover member receivable on the plate portion for cooperation with the depressed part of the plate to form fuel conducting passages for flash-back ignition of the burners, said cover member having downwardly, 10 extending ribs engageable with the groove walls.
6. In a stove, a plurality of burners, a pilot light, an interceptor plate extending between 15 said burners, said plate having depressed grooves formed therein extending between the pilot and the burners, and a cover member for said grooves comprising channels of inverted trough shape receivable in the grooves and held therein only by gravity to form fuel conducting passages for flash-back ignition of the burners.
7. In a stove, a plurality of burners, a pilot light, an interceptor plate extending between said 20 burners, said plate having a central depressed portion with a pilot light opening formed therein and grooves extending from the central portion to the burners, a cover for said central portion and grooves receivable on said plate for cooperation with the grooves to form fuel conducting passages for flash-back ignition of the burners, said cover having an opening therein concentrically related to the pilot light opening of the depressed plate portion, and interfitting means 25 engaging the plate and cover in predetermined positioning.
